UNITED STATES PATENT OFFICE.

EMIL TYDEN, OF HASTINGS, MICHIGAN.

SEAL-LOCKED CAN.

1,080,183.

Specification of Letters Patent.

Patented Dec. 2, 1913.

Application filed March 5, 1913. Serial No. 751,984.

To all whom it may concern:

Be it known that I, EMIL TYDEN, a citizen of the United States, residing at Hastings, in the county of Barry and State of Michigan, have invented new and useful Improvements in Seal-Locked Cans, of which the following is a specification, reference being had to the accompanying drawings, forming a part thereof.

10 The purpose of this invention is to provide an improved construction of a can or the like, such, for example, as a milk-ship-
ping can, which shall be adapted to be se-
cured with a lock adapted to be sealed to
15 prevent tampering.

It consists of the elements and features of construction shown and described as indicated in the claims.

In the drawings:—Figure 1 is a partly 20 sectional side elevation of a milk can of a common form, modified so as to embody this invention, and provided with a lock, section being made radially with respect to the can at a vertical plane adjacent to the position 25 of the lock. Fig. 2 is a section at the line 2—2 on Fig. 1. Fig. 3 is a detail elevation of the parts shown in Fig. 1 looking in the direction of the arrow 3 on Fig. 1. Fig. 4 is a section at the line 4—4 on Fig. 1 show-
30 ing the device sealed. Fig. 5 is a plan view of the seal employed in the lock shown. Fig. 6 is a detail section similar to Fig. 2, but showing the form of the cover member of the can modified in a minor detail. Fig. 35 7 is a plan view of the seal in a slightly modified form.

The can represented in the drawings is, in general, of familiar construction, comprising a cylindrical body, 1, having a flar-
40 ing upper marginal portion, 2, and a cover, 3, which telescopes within the cylindrical body, and which has at its upper end a flange, 4, which overhangs the flaring upper end of the body, and is curved down-
45 ward to engage by its wired margin, 4^a, with the wired margin of said flared upper end of the body.

For locking the body member and cover member of this can together at closed position, there is mounted on the outside of the body, preferably in the angle between the cylindrical portion and the flaring or conical portion, a bolt housing, 6, in which there is provided a bolt, which, as illustrated, is a seal bolt or bolt and seal combined, 7. This bolt is made of sheet material, preferably

metal, and is mounted for sliding in the housing radially with respect to the can body; that is, transversely to the telescoped walls of the body and cover. At the inner 60 end of the seal bolt member, 7, it is prefer-
ably formed with a tongue, 9, narrow in
comparison with the entire width of the seal bolt, and the can body is apertured in
the plane of the slide-way provided in it 65 for the seal bolt, to permit this tongue of
the latter to protrude through said body
member of the can for engagement with the
cover member; and said cover member is
provided with a circumferentially-extend- 70
ing shoulder, 11, facing upwardly for en-
gagement with the bolt tongue, 9, to prevent
the withdrawal of the cover from the body.
This shoulder is most conveniently, and
therefore preferably, produced by forming 75
a circumferentially-extending groove, 12, in
the outer surface of the cover, such groove
being rolled or pressed in the sheet metal of
the cover by methods familiar to the sheet
metal working art. Other methods of form- 80
ing the shoulder, however, are obvious. The
shoulder, and the groove when employed as
a means of producing the shoulder, are ex-
tended circumferentially of the can, prefer-
ably entirely around the same, so as to avoid 85
the necessity of turning the cover to any
particular position in order to permit it to
be locked by the seal bolt. It is not neces-
sary that the groove or shoulder should ex-
tend entirely around. It may be sufficient 90
for practical convenience to extend it
through a considerable segment, say ninety
degrees of the circumference of the can
body; but when extended less than the en-
tire circumference, it must be terminated by 95
a stop shoulder to prevent the cover from
being disengaged from the bolt by rotating
it. When the groove is employed for the
purpose of producing the shoulder, 11, the
stop shoulder, 13, (see Fig. 6) necessarily 100
results from limiting the groove to a por-
tion of the circumference.

Obviously, a great variety of means could be employed for retaining the bolt in locking position. The preferred means consists in 105
what is commonly known as sealing bolt;
that is, providing means by which a sealing
element is connected with the bolt so as to
secure it in locking position, which sealing
element must be broken before the bolt can 110
be withdrawn. A great variety of well-
known sealing devices could be employed for

securing the bolt in locking position. The preferred form consists in making the bolt so that it is itself a seal, or comprises as a part of itself the sealing element. For this purpose, the bolt is formed as shown in Fig. 5, having an aperture, 7^b, into which a tongue projects from one margin of the aperture, said tongue standing normally in the plane of the sheet of which the bolt is made, and in no wise interfering with thrusting the bolt in its slide-way in the housing to move it to or from locked position. The housing, 6, is formed with an aperture, 6^b, transverse to the slide-way, 6^c, in which the seal bolt operates. This aperture, 6^b, extending entirely through the housing from side to side is positioned so that it approximately registers with the aperture, 7^b, of the seal bolt when the latter is at locking position. Speaking more accurately, the relation of said transverse aperture, 6^b, to the features of the seal bolt is that at the locking position of the latter, the vertical edge of the aperture, 6^b, remote from the can body, coincides substantially with the vertical edge of the tongue, 7^c, remote from the can body at the locking position of the bolt; and the aperture, 6^b, of the housing extends so as to expose the entire area of the tongue, 7^c, at said locking position. When the seal bolt has been thrust into locking position, the operator thrusting a finger through the aperture, 6^b, of the housing may bend the tongue, 7^c, out of the plane of the seal bolt into position transverse to said plane, thereby causing said remote edge of the tongue to extend across the said remote edge of the aperture and prevent the withdrawal of the seal bolt. The seal bolt is of such material, and the tongue is so constructed, that upon bending the tongue back to its original normal position, it will break off from the body of the seal, and the seal may then be withdrawn, unlocking the can. The adaptation of the tongue, 7^c, to be bent, as described, without breaking, and to break from being bent back to original position, may be a result of the character of the material of which the seal bolt is made, in view of the abrupt angles which the lateral edges of the tongue make with the edge of the aperture from which the tongue protrudes; that is, the tongue may be adapted to thus break without any special means for weakening it at the line at which the folding and breaking are to occur; but preferably, the tongue is weakened at this line by reducing its connection with the body of the seal at the margin of the aperture to a mere neck, 7^d, or two necks, 7^e, 7^f, as shown in the form represented in Fig. 7.

The tongue, 7^c, and the aperture, 6^b, in the housing through which the tongue is exposed and accessible, are designedly made large enough so that the tongue can receive

an identifying mark, indicated by the characters, X, Y, Z, in the drawing. The seal bolt has sufficient extent outside the housing when it is in locked position to be provided at its exteriorly-extending part with any other identifying mark or number, as indicated by the number, 123, shown upon said protruding part of the seal in the drawings. 70

Preferably, the seal bolt has a cover-engaging tongue, 9, positioned a little off the center of width of the bolt so that a little accommodation to variation of position of the groove shoulder, 11, can be obtained by using the seal with one edge or the other up. 75

I claim:—

1. In a can or the like having a cover member telescoping with the body member, the combination with said members of a lock mounted on the outer side of the outer of said telescoped members, comprising a bolt thrust through said outer member for locking, the inner member having a circumferentially-extending groove in its outer surface positioned for engagement of the bolt therewith. 80

2. In a can or the like, comprising a body member and a cover member telescoping with each other, the outer of said members having a flaring upper part, the combination of said members with a lock mounted on the outside of such flaring part having a bolt thrusting inward, the inner member having an exterior groove extending circumferentially at a position for engagement of the bolt therewith. 90

3. In a can or the like which comprises a body member and a cover member telescoped with each other, the combination with said members of a seal lock comprising a housing mounted upon the outer side of the outer of said telescoping members, said outer member being apertured for the thrust of a bolt therethrough, and the inner member having means for engagement of a bolt thrust through said aperture, said housing having a slide-way for a flat seal bolt, which slide-way registers with the aperture of the outer member, and an aperture extending through the housing transversely of said slide-way, and a flat seal bolt adapted for sliding in said slide-way and terminating for engagement with the inner of the two can members, said seal bolt having intermediate its ends a tongue which at the locking position of the bolt is exposed in said transverse aperture of the housing, said tongue being bendable in the aperture transversely of the slide-way and adapted to break upon being bent back to its original plane. 100

4. In a can or the like which comprises a body member and a cover member telescoped with each other, in combination with said members, a seal lock comprising a housing mounted upon the outer side of the 110

- outer of said telescoping members, said outer member being apertured for the thrust of a bolt therethrough, and the inner member having means for engagement of a bolt 5 thrust through said aperture, said housing having a slide-way for a flat seal bolt, which slide-way registers with the aperture of the outer member, and having a shoulder transverse 55 to the slide-way facing toward the can at a short distance away from the outer surface of the latter; in combination with a flat seal bolt adapted for sliding in the slide-way and terminating for engagement with the inner 60 of the two can members, said seal bolt having a projection which, at the locking position of the bolt, stands inward from said inwardly-facing shoulder of the housing, said tongue being bendable to stand across 65 the shoulder, preventing the withdrawal of the seal bolt, and adapted to break from being bent back to its original plane.
7. In a can or the like which comprises a body member and a cover member telescoped with each other, the combination with said members of a seal lock comprising a housing mounted upon the outer side of the outer of said telescoping members, said outer member being apertured for the thrust of a bolt 70 therethrough, and the inner member having means for engagement of a bolt thrust through said aperture, said housing having a slide-way for a flat seal bolt, which slide-way registers with the aperture of the outer member, and an aperture extending through the housing transversely of said slide-way, and a flat seal bolt adapted for sliding in 75 said slide-way and terminating for engagement with the inner of the two can members, said seal bolt having a portion which at the locking position of the bolt is in position for bending out of its normal plane into the transverse aperture of the housing, said portion being bendable transversely of the 80 slide-way to cause it to stand in said transverse aperture, and being adapted to break upon being bent back into its original plane. 85
5. In a can or the like which comprises a body member and a cover member telescoped with each other, the body member 90 being flared at its upper end and the cover member having a flange overhanging said flaring upper end of the body member, a lock for securing said body and cover members together comprising a housing mounted upon the outer side of the body member; a bolt mounted in said housing for locking and unlocking movement and projecting through the flaring upper end portion of the outer member for engagement with the 95 cover member, said cover member having on its outer surface for said engagement a circumferentially-extending upwardly-facing shoulder.
6. In a can or the like which comprises a body member and a cover member telescoped with each other, a seal lock comprising a housing mounted upon the outer side of the outer of said telescoping members, said member being apertured for the thrust of a bolt therethrough and the
